ROTARY PUMP OR MOTOR

Ferdinand M. Weyer, Detroit, Mich., assignor to
Marine Products Company, Detroit, Mich., a
corporation of Michigan

Original application April 17, 1947, Serial No.
742,168. Divided and this application Decem-
ber 26, 1950, Serial No. 202,715

4 Claims. (Cl. 103—117)

1

This invention relates to fluid pressure pumps or motors.

One object of this invention is to provide a fluid pressure pump or motor having a rotor with vanes of resilient material on a rotary shaft mounted in a casing having opposite inner end walls inclined toward one another at angles of slightly less than right angles to the axis of rotation of the rotor shaft, the resilient vanes flexing as they engage these inclined end walls so as to create a pumping action by forcing liquid outward through an outlet port in the casing and drawing liquid inward through an inlet port in the casing.

Another object is to provide a fluid pressure pump or motor of the foregoing character, wherein the vanes are preferably arranged in approximately V-shaped or herringbone formations on opposite sides of a central disc-shaped rib projecting radially outward from the hub of the rotor.

Another object is to provide a modified fluid pressure pump or motor having a casing and rotor of the foregoing character except that the vanes are substantially straight in that they are substantially perpendicular to the plane of the central disc-shaped rib rather than inclined at an angle thereto, as in the V-shaped or herringbone formations of the other form of the invention.

This application is a division of my co-pending application Serial No. 742,168 filed April 17, 1947, now Patent No. 2,573,819, for Rotary Pump or Motor.

In the drawings:

Figure 1 is a central vertical longitudinal section through a fluid pressure pump or motor, according to one form of the invention;

Figure 2 is a vertical cross-section taken along the zigzag line 2—2 in Figure 1;

Figure 3 is a horizontal section, with the rotor in top plan view, taken along the curved line 3—3 in Figure 2, showing the flexing of the rotor vanes against the inclined casing end walls;

Figure 4 is a top plan view of a modified rotor with straight vanes removed from the pump or motor; and

Figure 5 is a side elevation of the modified rotor shown in Figure 4.

Referring to the drawings in detail, Figure 1 shows a fluid pressure pump or motor, generally designated 10, according to one form of the invention and including a base 11 with a central pedestal 12 having a horizontal bore 13 therein. Radiating outward from the central pedestal 12

2

which forms a journal bearing for a shaft 14, is a cup-shaped housing or casing 15. The housing or casing 15 consists of a disc-like radial wall 16 and a cylindrical axial wall 17 having a cylindrical bore 18 therein closed by a disc-like end plate 19 bolted thereto as at 20. The end plate 19 is provided with a reduced diameter portion 21 which extends into the cylindrical chamber 18.

10 The housing or casing 15 has radially extending inlet and outlet ports 30 and 31 respectively (Figure 2) formed in radially extending bosses 32 and 33 with threaded openings 34 and 35 to which the intake and discharge pipes are connected. Mounted on the inner end of the shaft 14 and splined thereto as at 36 (Figure 1) is a rotor 37. The rotor 37 consists of an annular sleeve 38 which is bored and grooved to fit the splines 36, and which has an annular ridge 39 running around the central portion thereof. Mounted upon the sleeve 38, which is preferably of metal, is the hub 40 of the vane unit 41, which is formed of elastic deformable material, such as rubber or synthetic rubber. The vane unit 41 has a central disc-shaped rib 42 projecting outward from the hub 40, and the rib 42 carries radially-extending vanes 43, also of elastic deformable material (Figure 4). The vanes 43 are preferably arranged in approximately V-shaped or herringbone formations on opposite sides of the rib 42 and are cut away as at 44 (Figure 1) where the disc-shaped rib 42 joins the hub 40. The gaps 44 between the vanes 43 and the hub 40 provide flexibility for the flexing 30 of the vanes 43 parallel to the axis of the pump as they pass between the inclined end walls of the casing 15, as described below in connection with the operation of the invention. The vanes 43 are so inclined relatively to the disc-shaped 35 rib 41 that their ends resemble arrow heads aimed in the direction of rotation of the rotor. The end portions 45 of the hub 40 project outward upon the ends of the vanes 43 (Figure 3), and also have annular grooves 46 therein.

40 Leading into the bore 13 is a transverse threaded hole or port 47 (Figure 1) into which is threaded the stem 48 of an oil cup 49. The latter is of a conventional pattern, having a lid 50 pivoted thereto at 51 so as to permit the insertion of oil or other lubricant for lubricating the shaft 14. The right-hand end of the bore 13 is provided with an annular cavity 52 containing annular packing 53 and compressed by 55 an annular gland or nut 54 threaded therein as

at 55. This backing 53 prevents the loss of the lubricant along the shaft 14.

Mounted on the outer end of the shaft 14 and secured thereto as by the set screw 56 is the hub 57 of a pulley 58 which is provided with a suitable annular groove 59 for engagement by a driving belt (not shown). The pulley 58 is a conventional type and for purposes of convenience is shown as having a V-groove to accommodate a V-belt. It will be evident, however, that any other type of belt or sprocket may be used in order to drive the shaft 14.

The modified rotor 60 shown in Figures 4 and 5 is generally similar to the rotor 37 shown in Figures 1 to 3 inclusive and has a similar central sleeve 61 on which is mounted the hub 62 of a rotor unit 63 of elastic deformable material, such as rubber or synthetic rubber. The rotor 60 is also provided with a central disc-shaped rib 64 with vanes 65 arranged in planes which are substantially perpendicular to the plane of the rib 64 instead of being inclined at an angle thereto, as in the principal form of the invention. The vanes 65, like the vanes 43, are cut away so as to provide caps 66 adjacent the hub 62, this construction permitting free flexing of the vanes 65. The remainder of the rotor 60 is substantially of the same construction as that of the rotor 37, and its operation is similar. The rotor 60, however, is capable of rotating in opposite directions, whereas the rotor 37 is preferably adapted to rotate in one direction only.

The housing or casing 15 contains a chamber 72 bounded by the cylindrical bore 18 and the opposite inner end walls 75 and 76 of the end plate 19 and housing or casing wall 16, respectively. The end wall 75 is inclined at slightly less than right angles to the axis of the rotor shaft 14, whereas the end wall 76 is also inclined at slightly less than right angles to the axis of the rotor shaft 14 (Figure 1). Because of this construction, the inner end walls 75 and 76 are slightly closer together at the top of the chamber 72 than at the bottom thereof, so that they converge towards the ports 30 and 31. The end walls 75 and 76 are recessed to receive the ends of the hub portions 38, 40 of the rotor 37.

In the operation of the invention as a pump, power is applied to rotate the shaft 14 and consequently the rotor 37 in a counterclockwise direction. As the vanes 43 pass from the bottom of the casing 11 to the top thereof, the converging of the end walls 75 and 76 causes the vanes 43 to flex inward in an axial direction, thereby bringing about a pumping action with respect to the liquid in the chamber 72 and causing liquid to be drawn in through the inlet port 30 and forced out through the exhaust port 31.

The operation of the pump or motor 10 as a motor is brought about by supplying pressure fluid to one of the ports, this causing the rotor 37 to rotate and impart rotation to the shaft 14 before being discharged through the outlet port. The vanes 43 flex laterally as before as they pass from the bottom of the chamber 72 to the top thereof, because of the converging of the end walls 75 and 76.

While the intake and discharge ports 30 and 31 have been described as circumferentially spaced, they are not necessarily located entirely on the peripheral portion 17, but may

extend partially down into the side walls or be located in the side walls 16 and 19 adjacent the periphery. This construction is employed in high-speed installations where the centrifugal force arising from the rotating liquid becomes unduly great.

The operation of the pump or motor 10 when equipped with the modified rotor 60 shown in Figures 4 and 5 is generally similar to the operation of the pump or motor when equipped with the rotor 37 of Figures 1 to 3 inclusive, except that the rotor 60 is capable of rotating in opposite directions, whereas, as previously stated, the rotor 37 is preferably adapted to rotate in one direction only, but at an efficiency somewhat higher than that of the rotor 60. Thus, the rotor 37 is preferably used where there is to be rotation in one direction only and the rotor 60 is used where it is necessary to provide rotation in opposite directions. Of course, where the rotor 60 is rotated in opposite directions, the intake port for one direction becomes the discharge port for the opposite direction and vice versa.

What I claim is:

1. A rotary pump or motor comprising a hollow casing having an approximately cylindrical pump chamber with axially-spaced end walls and a cylindrical peripheral wall joining said end walls, said casing having circumferentially-spaced fluid intake and discharge ports, a shaft rotatably mounted in said casing, at least one of said end walls being inclined relatively to the axis of said shaft substantially entirely across said chamber and causing said end walls to converge toward said ports, and a rotor having a hub portion mounted on said shaft and having radially-extending vanes of elastic deformable material, the peripheral edges of said rotor vanes engaging said cylindrical wall and the side edges thereof engaging said inclined end walls and flexing parallel to the axis of the pump in response to the convergence thereof, said vanes at their inner ends being cut away from said hub portion.

2. A rotary pump or motor comprising a hollow casing having an approximately cylindrical pump chamber with axially-spaced end walls and a cylindrical peripheral wall joining said end walls, said casing having circumferentially-spaced fluid intake and discharge ports, a shaft rotatably mounted in said casing, both of said end walls being inclined relatively to the axis of said shaft substantially entirely across said chamber and causing said end walls to converge toward said ports, and a rotor having a hub portion mounted on said shaft and having radially-extending vanes of elastic deformable material, the peripheral edges of said rotor vanes engaging said cylindrical wall and the side edges thereof engaging said inclined end walls and flexing parallel to the axis of the pump in response to the convergence thereof, said vanes at their inner ends being cut away from said hub portion.

3. A rotary pump or motor comprising a hollow casing having an approximately cylindrical pump chamber with axially-spaced end walls and a cylindrical peripheral wall joining said end walls, said casing having circumferentially-spaced fluid intake and discharge ports, a shaft rotatably mounted in said casing, at least one of said end walls being inclined relatively to the axis of said shaft substantially entirely

across said chamber and causing said end walls to converge toward said ports, and a rotor having a hub portion mounted on said shaft and having radially-extending vanes of elastic deformable material, the peripheral edges of said rotor vanes engaging said cylindrical wall and the side edges thereof engaging said inclined end walls and flexing parallel to the axis of the pump in response to the convergence thereof, said vanes at their inner ends being cut away from said hub portion, said end walls having recesses adjacent said shaft, and the opposite ends of said rotor hub portion extending into said recesses.

4. A rotary pump or motor comprising a hollow casing having an approximately cylindrical pump chamber with axially-spaced end walls and a cylindrical peripheral wall joining said end walls, said casing having circumferentially-spaced fluid intake and discharge ports, a shaft 20 rotatably mounted in said casing, at least one of said end walls being inclined relatively to the axis of said shaft substantially entirely across said chamber and causing said end walls to converge toward said ports, and a rotor having a hub portion mounted on said shaft and having radially-extending vanes of elastic deformable material, the peripheral edges of said rotor

vanes engaging said cylindrical wall and the side edges thereof engaging said inclined end walls and flexing parallel to the axis of the pump in response to the convergence thereof, said vanes 5 at their inner ends being cut away from said hub portion, said casing having an end closure member secured thereto, and one of said inclined end walls being disposed on said end closure member.
